LAUNDRY MACHINE

Peyton W. Douglas, Syracuse, N. Y., assignor to
Easy Washing Machine Corporation, Syracuse,
N. Y., a corporation of Delaware

Application June 16, 1948, Serial No. 33,370

11 Claims. (Cl. 210—63)

1

This invention relates to balancing of centrifugal extracting apparatus, the invention having particular applicability to washing machines employing centrifugal extraction for damp drying.

In centrifugal extracting apparatus, and particularly where applied to washing machines, there is usually difficulty in achieving uniform distribution of the load within the extractor so that balanced conditions prevail throughout the extracting speed range employed. The problem is particularly troublesome in laundry apparatus for the reason that various textiles tend to retain different percentages of moisture when in soaking wet condition, and consequently although distributed apparently evenly from the volumetric standpoint, the actual weight factor is practically certain to be substantially out of balance. The problem has been enhanced by the introduction of automatic laundry apparatus wherein reliance for the proper distribution of the laundry prior to centrifuging is left entirely to chance, as, for example, a haphazard tumbling action and wherein the skill of the operator in judging the proper distribution of the laundry during loading is not utilized. Additionally, even though laundry may be properly distributed as by careful placement of an operator prior to rotation of the extractor basket, rotation may cause the material to become displaced and thereby create an unbalanced condition, this being particularly true of horizontal axis machines. The problem is so severe that in many instances heavy weights arranged in balanced relation are employed to increase the rotating mass and thereby reduce the percentage of possible off-balance and the off-center radius of the center of mass. In other instances, the journals in which the extractor rotates are connected to heavy stationary masses which are expected to reduce the serious vibration which would otherwise result from the high speed rotation of the unbalanced laundry load. Resort to such methods does not tend to eliminate the actual unbalance at the source.

It is an object of the present invention to automatically self-compensate a centrifugal extractor for an unbalanced condition.

A further object of the invention is to utilize the unbalanced load in a centrifugal extractor automatically in a manner such that as the mass is brought to speed, the extracted water will be delivered to balancing compartments so arranged as to substantially balance the unbalanced load which contained the water to be extracted.

A still further object of the invention is to provide such a balancing system which may be applicable to automatic washing machines having included in the cycle of operation an extractor stage and in which the machine may have a vertical or horizontal axis or inclined if desired.

The above and other novel features of the invention will appear more fully hereinafter from the following detailed description when taken in conjunction with the accompanying drawings.

2

It is expressly understood, however, that the drawings are employed for purposes of illustration only and are not designed as a definition of the limits of the invention, reference being had for this purpose to the appended claims.

In the drawings, wherein like reference characters indicate like parts:

Figure 1 is a transverse axial section through a washing machine of the horizontal axis type to which the invention is applied;

Figure 2 is a section taken on the line 2—2 of Figure 1, showing certain duct details;

Figure 3 is a section taken on the line 3—3 of Figure 1, showing additional duct details as well as relative arrangement of the balancing compartments;

Figures 4 and 5 are diagrammatic figures showing the flow of fluid during rotation of the apparatus of Figures 1 and 3 for extracting purposes;

Figure 6 is a transverse axial section of a vertical axis machine having the invention applied thereto; and

Figure 7 is a transverse section taken through Figure 6 on the line 7—7, showing ducts and balancing compartments.

Referring to the drawings, and more particularly to Figures 1, 2, and 3, there is illustrated a washing machine of the rotating horizontal axis cylinder type, comprising a washing drum 10 rotatably mounted in a stationary housing 12 in which is enclosed a rear bearing framework 14. The drum 10 has an outer wall 16 extending forwardly and tapered inwardly and formed into a front wall 18 having a centrally located circular loading aperture 20. To the rear of the outer wall 16 are secured spaced back walls 22 and 24, which are connected together to form a unitary structure by vanes 26 and to which structure is secured a hollow rear bearing trunnion 28. The trunnion 28 is journaled in spaced bearings 30 mounted upon the framework 14, the same being forked as at 32 to receive a drive pulley 34 between the spaced bearings 30. The forward end 35 of the cylinder 16 is also supported for rotation by means of a rotatable circular door 36 mounted upon a bearing 38 and stationary stub shaft 40, the latter being carried upon a stationary door 42 arranged in the front wall 44 of the cabinet 12, the door 42 being hinged to the front wall in any suitable manner. The circular door 36 is adapted to engage a sealing ring 46 of any desired type, that shown being carried in an annular recess 48 surrounding the loading aperture 20 of the cylinder 16, and the construction is such as to provide axial pressure of the door 36 against the seal 46 when the door is held in closed position.

The outer wall 16 of the drum 10 is imperforate and provided with a plurality of baffles 50 extending lengthwise thereof, preferably uniformly spaced, and in the arrangement shown, there are three in number. Water is admitted to the cylinder through the hollow trunnion 28 by means of a supply pipe 52 terminating in a spray rosette

54 inside of the back wall 22. Any suitable seal as may be found desirable may be provided between the stationary pipe and the wall 22 as will be well understood in the art. The supply pipe 52 is fed from hot and cold water lines 56 and 58 and a suitable mixing valve 60 which may be of the electromagnetic controlled type if desired. Wash water is removed from the cylinder through ducts formed by the baffles 50, the same being formed as channel members as is more particularly shown in Figure 2. The channel members are provided with apertures 62 along their length on one side and adjacent the base, so that liquid may drain to the channel and thereafter be discharged to the rear of the cylinder in a 15 manner which will hereinafter appear.

The ducts 64 thus formed by the baffles 50 extend to the rear plate 22 and there connect to substantially arcuate passageways 66 which extend counterclockwise around the rear forward face of the back wall 22 approximately 120°. The direction and arcuate length of the ducts 66 is such that upon rotation of the cylinder in a counterclockwise direction, washing fluid contained within the cylinder 10 may not escape, since any tendency of wash fluid to flow through the ducts 66 is counteracted by the direction of rotation of the cylinder in a counter-clockwise direction as well as the capacity of the ducts 66 to conduct any substantial amount of fluid. By reference to Figure 3, it will be seen that while the duct 66a appears below the level L of the wash fluid, and therefore might conduct fluid through its length to the discharge end, it is rapidly turning in a counterclockwise direction (arrow A) so that only for a brief moment is the opposite end below the level L of the wash fluid, and before any substantial quantity of fluid may enter the duct, the discharge end has been elevated above the level, and such fluid as may have entered the duct is thereafter drained back into the cylinder. Such action occurs when the duct reaches the position in which the duct 66b appears. Thus, it will appear that the maintenance of fluid within the wash cylinder during the washing period depends upon the direction of rotation.

In order to effect drainage of washing fluid from the cylinder, rotation of the cylinder is reversed. The ducts 66 thereupon act as scoops and provide a bailing action. For this purpose, the outlet 68 of each of the ducts 66 at the discharge end lead into segmental compartments 70 located between the rear walls 22 and 24, the compartments being formed by such walls and the previously referred to vanes 26. The compartments are three in number to correspond to the sections between the baffles 50 and are each of like capacity and shape. Each compartment is bounded at one end by a vane and at the other end by an adjoining vane and a radial partition 72 such compartment as so bounded is substantially diametrically opposed to the corresponding internal segment within the drum. Partition 72 closes off the acute angular portion of the compartment which would be difficult to maintain clean, and further controls the effective center of the compartment, placing such center opposite the center of the corresponding segment. It will be seen that the vanes 26 are spiral in nature and terminate together at the center or axis of the cylinder, and the dihedral space 73 between such vanes at the center connects directly with the hollow trunnion 28.

From the foregoing, it will be appreciated that upon slow rotation of the cylinder in a clockwise

direction, any liquid discharged into the compartments 70 from the washing cylinder will in turn be scooped by the vanes 26 as rotation takes place, and lifted to the center or axis of the cylinder and thereby delivered to the hollow trunnion 28 whence the fluid may be discharged to a drain receptacle 74 and thereafter led off to a suitable drain connection 76. The operation just described requires that the clockwise rotation speed be not excessive, that is, that it be not so great as to be interfered with by centrifugal force which would, if sufficiently great, tend to cause the wash water to arrange itself upon the peripheral walls of the chambers 70 and resist the spiral lifting or pumping action of the spiral vanes 26. In practice, washing may be effected by a rotation of the cylinder in a counterclockwise direction at a speed in the neighborhood of 60 R. P. M., with a 20 inch diameter drum and suitable draining operation may be effected by clockwise rotation at a similar speed, these speeds being such as not to introduce centrifugal force to a sufficient extent to overcome the normal effect of gravity.

It will also be appreciated that the problem of balancing does not arise at these speeds, since the laundry material contained within the cylinder 10 will tumble about and constantly rearrange itself within the cylinder during rotation at such low speeds.

To centrifugally extract washing fluid entrained in the laundry after the draining operation has been completed as previously described by relatively slow rotation of the cylinder in a clockwise direction, the rotation of the cylinder 30 may be substantially increased in speed to as high as 600 R. P. M. or thereabouts, if desired. As the speed of the cylinder increases, the tumbling action of the laundry within the cylinder as previously described may tend to arrange the material 35 about the outer wall 16 of the cylinder 10, but as soon as a predetermined speed is reached, centrifugal force will approach the force of gravity and at this point the laundry will tend to retain its position against the outer wall 16; further increase of speed will increase the centrifugal force and hold the laundry as thus distributed against the outer wall 16 and prevent further displacement other than matting down of the laundry in response to further increase of centrifugal force and rotation speed.

Since the distribution which takes place is unlikely to arrange the laundry uniformly, and results in a haphazard distribution such that the weight of the laundry plus entrained water is 55 non-uniformly distributed about the cylinder, considerable vibration will result. Should the laundry load be composed of pile fabrics such as heavy toweling or chenille fabrics which are not of a length to permit even distribution around 60 the circumference of the cylinder, the unbalanced condition may be extremely severe because of the great amount of moisture entrained in such material. The unbalanced condition under such circumstances may be so severe as to strain the machine unduly and require an inordinate amount of power to increase the speed of rotation to a degree sufficient to perform the extracting operation. In fact, the unbalance may be so severe as to preclude any substantial increase in speed and thus prevent extraction.

From a consideration of the structure thus far described, it will be seen that as the speed of rotation reaches that necessary to provide sufficient centrifugal force to overcome the force of gravity, the effectiveness of the spiral vanes 26

to lift or direct liquid from the compartments 70 to the drain sleeve 28 terminates and thereafter any liquid delivered to the compartments 70 will be prevented from leaving such compartments. It will also appear that the conduits 66 are so arranged as to lead any liquid arriving in the space between two adjacent baffles 50 to a compartment 70 which is substantially diametrically opposite to the space between such baffles. Thus, as the speed of rotation is increased to a point where substantial centrifugal extraction commences, the liquid extracted from the laundry held by centrifugal force between any pair of baffles will be led to the chamber 70 at the opposite side of the cylinder. Accordingly, if the laundry contained within the cylinder is disposed unevenly, the moisture extracted from the laundry contained in the various spaces between the adjacent baffles 50 will also be uneven in substantially like proportion. By leading the extracted liquid to the chambers oppositely located, the extracted water automatically tends to counterbalance the uneven loading.

The balancing effect resulting, while in most cases not exact, is quite effective for the reason that the laundry in general, when sopping wet, weighs, with the water entrained, approximately double the weight of the same laundry after having been damp dried by centrifugal extraction. Thus, the amount of water removed and transmitted to the opposed chamber is about equal in weight to the laundry contained in the particular opposite sector when extraction has been completed. Thus, an approximate diametrical balance is established for each of the sectors between the baffles 50. Since a large portion of the entrained water is removed before full speed is attained, the balance is substantially established before full speed is reached, thus effectively relieving the strain which would otherwise be manifested by the non-uniform distribution.

It will be seen that the chambers 70 are located at a radial distance comparable to the laundry, a somewhat greater radius, however, being essential to assure flow of extracted water through the conduits 66, which for the purpose are provided with a slightly spiraled outer wall 67, the radius of which increases from the baffle end to the discharge port 68. Not only is the duct 66 provided with a spiral wall 67, but the cylinder wall itself, particularly adjacent the wall 22, is slightly spiraled between ducts as at 63, with offsets 61 so that extracted water tends to flow in the direction of arrow C, under centrifugal force to the ducts 64, and thence into the spiral ducts 66.

After extraction is completed, the speed of rotation is reduced and upon reaching a critical speed, the spiral vanes 26 act to lift or direct the water to the center and discharge the same to the hollow trunnion 28 and thence to drain. The operation is similar to that shown in my pending application Serial No. 775,236, filed September 20, 1947.

Reference to Figures 4 and 5 will diagrammatically illustrate the manner in which an unbalanced wash load W, sopping wet, will be subjected to centrifugal force tending to cause the entrained water to travel in the direction of the arrows E, such water ending up in the one of the pockets 70 diametrically disposed from the wash load to act as a counterbalance (see Figure 5).

Balancing by utilizing the foregoing principle may be accomplished in a vertical axis machine 75

such as that illustrated in Figures 6 and 7. Referring to Figure 6, there is shown a casing 100 mounted upon a base 102, to which is secured a bearing frame structure 104. Within the casing 100 is mounted a drum 106 having a bottom plate 108, and within which wash fluid is retained. The casing is provided with an access or loading door 101, having a resilient annular rubber-like sealing member 103, bearing lightly against a flange 105 in the upper open end of the drum 106. The wall of the drum 106 is imperforate and tapered slightly to provide a larger diameter at the bottom. The bottom plate 108 is also imperforate, and the drum is provided with a plurality of rib members 110 arranged upright along the inside side wall thereof at uniformly angularly spaced positions or regions A, B and C. The ribs 110 are provided with ports 112 connecting the drum with the channel 114 formed by the ribs. The lower end of the drum and bottom wall 108 is surrounded by a peripheral and bottom-enclosing chamber 116 formed by the end wall 118 which is upwardly and inwardly flared as at 120 and secured to the side wall of the drum 106 as at 122. The chamber 116 is divided into a number of arcuate spaces or regions D, E and F by radial partitions 124, the number of arcuate spaces being similar to the number of intervening arcuate spaces defined by the ribs 110 in the drum 106. The arcuate spaces between partitions 124 in the chamber are so oriented with respect to the spaces between the ribs 110 in the drum as to be oppositely disposed from one another. Within the drum 106 and adjacent the periphery of the bottom wall 108 are provided substantially arcuate passageways 126 connecting the interior of the ribs 110 with the spaces defined by the partitions 124, the conduits 126 in each case being of a length to connect the space within the tub between adjacent ribs 110 with the respective partition defined spaces in the chamber 116 substantially diametrically opposed thereto. The outer walls 127 of the conduits 126 may be slightly spiraled outwardly to assure flow therealong into the chamber 116. The region A is thus connected to the region D, B with E, and C with F.

The drum 106 is supported upon a hollow trunnion 128 journaled in the frame 104 and is adapted to be driven through a belt drive 130 by a motor 132, the drive thus provided being adapted for relatively high speed centrifugal extraction of wash or rinse water from laundry contained within the drum 106.

Extending through the hollow trunnion 128 and through a water-tight packing 134 in the tub bottom 108 is an agitator shaft 136 having secured at its upper end an agitator 138. The shaft 136 is adapted to be oscillatably driven by a suitable transmission 140 and drive motor 142, as will be well understood in the art. The agitator shaft 136 is hollow as at 144, and notched at its upper end as at 146 to provide mechanism for disengaging the agitator from the shaft 136. The hollow sleeve 148 of the agitator is provided with pins 150 engaging the notches 146 when in the position shown, and by means of an axially movable rod 152 bearing against the head 154 of the agitator, the same is adapted to be lifted a sufficient distance to clear the pins 150 above the notches 146 to disengage the agitator from the shaft 136. Any suitable means such as the lever 156 and a power actuation such as a solenoid 158 may be employed for shifting the rod 152 to disengage the agitator from the shaft 136. When so disengaged, it will be ap-

preciated that the agitator is free to rotate as, for example, during extracting rotation of the drum 106.

The hollow trunnion 128 connects at its upper end with the chamber 116 and at its lower end to the stationary sump 160, there being provided a water-tight packing connection 162 to the trunnion 128. A packing 163 is provided between the shaft 136 and the bottom wall of the sump 160. The sump 160 is connected through 15 a valve 164 to a pump 166. It will be appreciated that when the valve is closed, wash water may be retained within the chamber 116 and at a suitable level within the drum 106 for washing purposes; and that upon opening the valve 164, the drum 106 may be drained and the waste water suitably disposed of by the pump. The pump may be driven by a belt drive such as 168 from the motor 142, the drive being continuous. When the agitator 138 is elevated and disengaged from the agitator drive shaft 136 and the valve 164 open, the pump is effective to drain the waste from the sump, but when the valve 164 is closed, the pump runs free.

In operation, the valve 164 will initially be closed, a load of laundry placed within the tub 106 and a suitable supply of wash water delivered to the tub by the hot and cold water control valve 170 and inlet pipe 172. The agitator 138 is coupled to the agitator drive shaft 136 and the motor 142 started. Suitable detergent will be supplied to the wash water as desired. After completion of the washing action, the drain valve 164 will be opened and wash water delivered to waste. If desired, rinsing water may then be introduced into the tub 106 while the valve 164 is again closed. The agitator may be operated during such rinse and thereafter the rinse water drained by opening the valve 164.

During draining of the wash or rinse water, the agitator will preferably be stopped by actuation of the solenoid 158 and lifting of the agitator from engagement with the drive shaft 136. The clothes will then lie upon the bottom plate 108 in a soaking condition, under which circumstances, the weight of water plus the weight of clothes will approximate double the weight of the clothes after being damp dried by centrifugal extraction. At this point, the motor 132 is energized, the valve 164 allowed to remain open, and the tub 106 caused to gather speed. The centrifugal action will cause the water retained in the clothes to be thrown therefrom and delivered into the conduits 114. It will be seen that more water will be extracted centrifugally from the side of the tub having the greater quantity of clothes. The water thus extracted will flow down the conduit 114 into the connecting arcuate conduit 126, whence it will be delivered into the space diametrically opposed to the space within the chamber 116 and diametrically opposed to the space in which the heavier mass of laundry is positioned. The water so distributed into the chamber 116 will be held therein by centrifugal force, and will be in a substantially proper quantity to assist in counterbalancing the out of balance of the laundry within the tub 106 as a result of the uneven distribution. The laundry in the other spaces distributed between the conduits 114 will also lose water by centrifugal extraction, which water will be delivered to the respectively opposed spaces within the chamber 116, and the quantity will be of course less than that derived from the heavier mass of laundry in the space first referred to. For ex-

ample, if the laundry is so distributed that a major part thereof lies in the region A, $\frac{1}{2}$ of the soaking wet weight thereof will be delivered to the chamber 116 in the region D. Likewise, the extracted water from the regions B and C will be delivered to those regions E and F, respectively. The water retained in the chamber 116 will thus be distributed in a pattern such as to counterbalance the uneven distribution of the weight of the damp dry laundry in the drum 106. Since the radius of the chamber 116 is somewhat similar to the radius of the tub 106 and the amount of water which will be centrifugally extracted will approximate $\frac{1}{2}$ of the weight of the soaking wet laundry before extraction takes place, it will be seen that as speed is increased and extraction carried on, the water contained in the respective spaces of the chamber 116 will approximately counterbalance the damp dry laundry contained within the tub. Under certain circumstances, the balancing effect may be quite exact and under other circumstances, it will be appreciated that the effect of retaining the extracted water in the manner described will produce substantial balance or at least reduce any unbalanced condition which may have been the result of uneven distribution by such a substantial amount as to practically eliminate vibration. Counteraction of the unbalanced condition will take place rapidly as speed is attained, since a large percentage of the water is extracted in the initial part of the extraction period, and even before any substantial speed is reached.

As soon as sufficient time has elapsed for extraction, the motor 132 is de-energized and as the tub 106 is allowed to come to rest, the water retained in the chamber 116 will flow into the sump 160, from which it will be pumped to waste by the pump 166.

While the invention has been illustrated in modified forms, it is to be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

1. In a centrifugal extractor type laundry apparatus, a washing cylinder, means for rotating said cylinder to cause the same to act as a centrifuge, means substantially uniformly dividing said cylinder internally into shallow water-retaining sectors, counterbalancing compartments carried by said cylinder corresponding in number to said sectors, and conduit means connecting each of said sectors with a corresponding compartment diametrically opposed thereto for leading centrifuged liquid from each sector into the corresponding counterbalance compartment.

2. In a centrifugal extractor type laundry apparatus, a washing cylinder, means for rotating said cylinder to cause the same to act as a centrifuge, means substantially uniformly dividing said cylinder internally into shallow water-retaining sectors, counterbalancing compartments carried by said cylinder corresponding in number to said sectors, conduit means connecting each of said sectors with a corresponding compartment diametrically opposed thereto for leading centrifuged liquid from each sector into the corresponding counterbalance compartment, and means for draining said compartments in response to a reduction in the speed of rotation of

said cylinder well below that employed for centrifuging.

3. In a centrifugal extractor type laundry apparatus, a washing cylinder, means for rotating said cylinder to cause the same to act as a centrifuge, means substantially uniformly dividing said cylinder internally into shallow water-retaining sectors, counterbalancing compartments carried by said cylinder corresponding in number to said sectors, conduit means connecting each of said sectors with a corresponding compartment diametrically opposed thereto for leading centrifuged liquid from each sector into the corresponding counterbalance compartment, and means for draining said compartments responsive to reducing the speed of rotation below a predetermined critical speed.

4. In a centrifugal extractor type laundry apparatus, a washing cylinder, means for rotating said cylinder to cause the same to act as a centrifuge, means substantially uniformly dividing said cylinder internally into shallow water-retaining sectors, a plurality of counterbalancing compartments carried by said cylinder corresponding in number to said sectors, substantially arcuate conduits connecting each of said sectors with a corresponding compartment diametrically opposed thereto for leading centrifuged liquid from each sector into a counterbalance compartment, said conduits all extending in the same circumferential direction and adapted to prevent liquid transferred to said compartments from returning to said cylinder upon reducing speed from centrifuging speed while rotating in the same direction.

5. In a centrifugal extractor type laundry apparatus, a washing drum, means for rotating said drum to cause the same to act as a centrifuge, water-directing means dividing the internal surface of said drum into sectors, a plurality of counterbalancing compartments carried by said drum and circumferentially disposed therearound, means for leading centrifuged liquid from each sector into a counterbalance compartment substantially diametrically opposed thereto.

6. In a centrifugal extractor type laundry apparatus, a washing drum, means for rotating said drum to cause the same to act as a centrifuge, water-directing means dividing the internal surface of said drum into sectors, a plurality of counterbalancing compartments carried by said drum and circumferentially disposed therearound, means for leading centrifuged liquid from each sector into a counterbalance compartment substantially diametrically opposed thereto, and means for draining said compartments in response to a reduction in the speed of rotation of said drum well below that employed for centrifuging.

7. In a centrifugal extractor type laundry apparatus, an extractor drum, means for rotating said drum to cause the same to act as a centrifuge, means dividing said drum wall into sectors of uniform arcuate length, a plurality of counterbalancing compartments carried by said drum uniformly angularly spaced, substantially arcuate conduit means for leading centrifuged liquid from each sector into a counterbalance compartment substantially diametrically opposed thereto.

8. In a centrifugal extractor type laundry apparatus, an extractor drum, means for rotating said drum to cause the same to act as a centrifuge, means dividing said drum wall into sectors

of uniform arcuate length, a plurality of counterbalancing compartments carried by said drum uniformly angularly spaced, substantially arcuate conduit means for leading centrifuged liquid from each sector into a counterbalance compartment substantially diametrically opposed thereto, and means for draining said compartments in response to a reduction in the speed of rotation of said cylinder well below that employed for centrifuging.

9. In a centrifugal extractor type laundry apparatus, a washing drum having a tapered wall, means for rotating said drum to cause the same to act as a centrifuge, substantially elementally extending ribs dividing said drum into sectors of uniform arcuate length, a plurality of counterbalancing compartments carried by said drum corresponding in number to said sectors and arranged diametrically opposed thereto, said compartments being of greater radical distance from the drum axis than said sectors, means for leading centrifuged liquid from each sector into a counterbalance compartment substantially diametrically opposed thereto.

10. In a centrifugal extractor type laundry apparatus, a washing drum having a tapered wall, means for rotating said drum to cause the same to act as a centrifuge, substantially elementally extending hollow ribs dividing said cylinder into uniform sectors, said ribs being apertured on one side to connect with a sector, a plurality of counterbalancing compartments carried by said cylinder and opposed to said sectors, and radially outwardly spaced with respect to said sector drum wall, substantially arcuate conduit means for leading centrifuged liquid from the end of each rib into a counterbalance compartment substantially diametrically opposed thereto, said conduits being sloped spirally outward, and means for draining said compartments in response to a reduction in the speed of rotation of said drum well below that employed for centrifuging.

11. In a centrifugal extractor type laundry apparatus, a washing drum having a tapered wall, means for rotating said drum to cause the same to act as a centrifuge, substantially elementally extending hollow ribs dividing said cylinder into uniform sectors, said ribs being apertured on one side to connect with a sector, a plurality of counterbalancing compartments carried by said cylinder and opposed to said sectors, and radially outwardly spaced with respect to said sector drum wall, substantially arcuate conduit means for leading centrifuged liquid from the end of each rib into a counterbalance compartment substantially diametrically opposed thereto, said conduits being sloped spirally outward from sector to compartment, and means including spiral vanes and a central discharge outlet for draining said compartments in response to a reduction in the speed of rotation of said drum well below that employed for centrifuging.
